PROCESS OF MAKING FLAME COLORING STICKS

Jonathan P. B. Fiske, Newton, Mass.

Original application October 29, 1940, Serial No. 363,240. Divided and this application February 24, 1943, Serial No. 476,942

4 Claims. (Cl. 18—58)

This invention relates to flame coloring material and more particularly to the process whereby such material is formed into sticks, bars or other easily handled articles to which is directed my Patent 2,320,330, granted May 25, 1943, of which patent the present application is filed as a division.

Sticks or other easily handled articles prepared from such material and comprising a flame coloring agent incorporated in a carrier, while solid at room temperature, are readily converted when placed in a fire into a liquid which spreads over and penetrates the logs or other fuel. The agent, preferably one or more chemical salts, e. g. the chloride, nitrate or sulphate of strontium, or barium, or the chloride or sulphate of copper, is thus distributed over the fuel, being caught by the cracks and crannies thereof, so that the coloring effect produced by the agent in the flames lasts for a long time and produces a wide-spread effect. The carrier may be any one of that class of substances which are solid at room temperature and melt into a liquid upon the application of heat. I have found paraffin wax gives superior results as a carrier, although other substances such as stearic acid or beeswax may be used if desired.

Heretofore it has been proposed to mix the flame coloring agent with the molten carrier and then to pour the mixture into molds. Such mixing of agent and carrier prior to pouring involves so many difficulties, including excessive time and excessive expense, that it has been found, after repeated trials, to be not commercially practical to manufacture flame coloring materials where such pre-mixing is involved. Moreover, this procedure has not been satisfactory for the reason that the flame coloring agent settled to the bottom of the molten carrier. It is not feasible to stir the mixture constantly while pouring and even if it were the sticks in different molds would not be uniform. Furthermore, it is not feasible to heat the carrier only to the point where the flame coloring agent will not settle rapidly because then the mix does not pour well.

The primary object of this invention resides in the manufacture of molded flame coloring articles consisting of a carrier and a flame coloring agent without the necessity of mixing the ingredients prior to molding.

This as well as other objects of the invention will appear from a consideration of the following description and of the drawing which forms a part thereof, and in which

Fig. 1 is a plan view of the mold in which the material is formed;

Fig. 2 is a cross-sectional view of the mold taken along the lines 2—2 in Fig. 1;

Fig. 3 is a side elevation of the mold;

Fig. 4 is a cross-sectional view of the die block of the mold taken along the line 4—4 in Fig. 1;

Fig. 5 is a similar view of the mold with which is assembled a charger unit for supplying the agent to the mold;

Fig. 6 is a sectional view of the mold with the agent in the cavities thereof;

Fig. 7 is a view similar to Fig. 6 with the agent and carrier in the cavities thereof;

Fig. 8 illustrates the die block with an ejector unit and the blocks of material after ejection from the mold; and

Fig. 9 is a perspective view of a finished stick.

The stick 10 of flame coloring material consists of a carrier 11 and a flame coloring agent 12. The carrier 11 is preferably of paraffin wax and the agent 12 is preferably copper chloride in the form of particles incorporated with the carrier and confined largely to one side of the stick (the upper side in Fig. 9). The process by which the stick 10 is made according to this invention is as follows: A predetermined amount of the copper chloride in the form of separate particles is placed in a mold. The paraffin wax converted by heat into a freely flowing liquid is poured into the mold on top of the particles until the mold is completely or substantially filled. While the liquid carrier readily fills the interstices between the particles of flame coloring agent the particles remain localized in the bottom of the mold because of their higher specific gravity. Since heated paraffin wax has a tendency to set quickly when no longer subjected to heat, the particles of agent are trapped and held in the cooling mass.

Suitable apparatus for carrying out this process illustrated in the drawing includes a mold 20 comprising a die block 21 and a bed 22. The die block 21 includes a plurality of cavities 23, three being here shown, in which the sticks of material are formed, such cavities being open at both ends and bound by inwardly inclined walls. The bed 22 comprises a base block 24, a layer 25 of sponge rubber, flannel, plush, or similar compressible material, and a sheet 26 of non-adhesive paper, e. g., glassine.

The die block 21 is suitably clamped upon the bed 22 by the coaction of hooks 27 carried by the base block 24 and pins 28 projecting outwardly from the die block. When assembled the sheet 26 closes the cavities 23 at the bottom. The

hooks 27 and pins 28 are so located that when the die block 21 is assembled with the bed plate 22, the bottom surface of the die block is depressed somewhat into the upper surfaces of the yieldable mass of the layer 25 so that the bottoms of the cavities are tightly sealed by the sheet 26 to prevent any escape of liquid therefrom during the formation of the sticks.

A charger unit 30 is employed in the feeding of the copper chloride crystals to the cavities 23 of the mold. That unit 30 comprises a box 31 having a plurality of pockets 32 in the base thereof and a slidable plate 33 held in close contact with the under face of the box by shouldered set screws 34 carried by the box and extending through slots 35 in the plate 33. The unit 30 is positioned on the block 21 by the reception of the dowell-pin heads of the screws 34 in apertures 45 in tongues 36 projecting from the sides of the block 21. The pockets 32 in the box are open at the bottom and when the unit is positioned on the block, register with the cavities 23 therein. The plate 33 in one position closes the pockets 32 (see Fig. 5). Slots 37 are provided in the plate which when the plate is shifted register with the pockets 32 and cavities 23.

A supply of the copper chloride crystals 12 is placed in the box 31 and the pockets 32, being closed by the plate 33, are filled evenly therewith, after which the plate 33 is pulled out to permit the crystals to drop into the cavities 23 of the die block 21. The charger unit 30 is then removed (see Fig. 6). The carrier forming material, e. g., paraffin wax, having been heated sufficiently for conversion into a liquid, is poured into the cavities on top of the crystals. After the carrier has set in the cavities 23 the die block 21 is separated from the bed 22 and supported in an inverted position over a removable pallet 40. Suitable means are then employed to drive the sticks 10 out of the cavities 23, such as an ejector unit 41 which comprises a base 42, bars 43 secured thereto and pins 44. The bars 43 are so dimensioned and positioned that they will register with and enter freely the open bottom ends of the cavities when the unit is positioned relative to the die block 21 by the entry of the pins 44 into the apertures 45 in the tongues 36. Sufficient pressure is exerted to depress the unit 41 and drive the sticks 10 out of the cavities onto the pallet 40.

Inasmuch as some of the flame coloring crystals are exposed at the surface of the sticks they tend to absorb moisture in damp weather. Crystals being intensely hydroscopic, absorb sufficient moisture from the air to cover, here and there, the surface of the sticks with a watery solution, and in the case of copper chloride, with green drops, which are very objectionable as they not only stain the paper box in which the sticks are packaged, but they stain the hands of any person using the sticks. To avoid this difficulty the sides of the sticks containing the crystals are painted with paraffin or other suitable waterproof material after they are removed from the mold. By localizing the crystals in one side of each stick

as illustrated in Fig. 9 it is necessary to paint only the upper portion of each stick after it has been deposited on the pallet 40. If the crystals were distributed throughout the entire stick it would be necessary to paint all sides of the stick. This would involve painting one side of the stick, waiting for it to dry, turning it over, and then painting the other side, thereby materially increasing the cost of production.

10 While one form of apparatus for carrying out this process has been described in detail, it will be understood that other forms of apparatus may be used if desired without departing from the spirit and scope of the invention as set forth in the following claims.

I claim:

1. That process of making units of flame coloring materials which comprises the steps of supplying discrete particles of a flame coloring agent to a mold, the particles being deposited at the bottom of the mold in a loose mass of considerable depth, pouring a liquefied carrier into the mold wherein it mixes with the agent and substantially fills the interstices between the particles throughout said mass, and allowing the carrier to set with the agent mixed therein.

2. That process of making sticks of flame coloring material consisting of particles of discrete chemical salt and a normally solid carrier which comprises the steps of placing chemical particles in a mold, the particles being deposited at the bottom of the mold in a loose mass of considerable depth, converting the carrier into liquid form, pouring the liquid carrier into the mold and onto the particles therein, the liquid substantially filling the interstices between the particles, and allowing said carrier to set with the particles incorporated with the carrier.

3. That process of making sticks of flame coloring material consisting of copper chloride and paraffin wax which comprises the steps of placing a predetermined amount of discrete copper chloride particles in a mold, the particles being deposited at the bottom of the mold in a loose mass of considerable depth, heating the paraffin wax to convert it into a liquid, pouring the liquid wax into the mold and onto the copper chloride, the liquid substantially filling the interstices between said particles, and allowing the wax to set in the mold to form a stick with the copper chloride incorporated with the wax.

4. That process of making a flame coloring unit which comprises separately applying to a mold discrete particles of flame coloring material and a liquefied carrier, the particles being deposited at the bottom of the mold in a loose mass of considerable depth, the carrier being sufficiently thin substantially to fill the interstices between the particles, and then allowing the carrier to set with the flame coloring material trapped therein, whereby the carrier may be poured while sufficiently fluid to fill the corners of the mold, the proportions of particles and carrier may be easily regulated and the particles may be localized at one side of the unit.
